UNITED STATES PATENT OFFICE.

THOMAS E. DUCKWORTH, OF COLFAX, LOUISIANA.

LUMBER LOADING AND UNLOADING DEVICE.

1,317,079.

Specification of Letters Patent.

Patented Sept. 23, 1919.

Application filed April 8, 1919. Serial No. 288,538.

To all whom it may concern:

Be it known that I, THOMAS E. DUCKWORTH, a citizen of the United States, residing at Colfax, in the county of Grant 5 and State of Louisiana, have invented certain new and useful Improvements in Lumber Loading and Unloading Devices, of which the following is a specification.

The invention relates to means for use in 10 connection with a coal car to facilitate the loading and unloading of lumber, the device being of such formation as to admit of its ready attachment to or disengagement from the side of a coal car or like carrier.

15 The drawing illustrates a preferred embodiment of the invention. However, it is to be understood that in adapting the same to meet different conditions, various changes in the form, proportion, and minor details 20 of construction may be resorted to without departing from the nature of the invention as claimed hereinafter.

In the drawing hereto attached,

25 Figure 1 is a view in elevation of a lumber loading and unloading device embodying the invention showing the same in position on the side of a car or other carrier, a portion of the side of the car being shown only.

30 Fig. 2 is a sectional detail on the line 2—2 of Fig. 1.

Fig. 3 is a sectional detail on the line 3—3 of Fig. 1.

35 Corresponding and like parts are referred to in the following description and indicated in the several views of the drawing by like reference characters.

The device comprises a hanger which 40 consists of companion hooks 1 and a connecting plate 2, the latter being flanged at its ends and secured in any manner to corresponding members of the hooks 1. The hooks are adapted to engage over the upper edge of the side 3 of a coal car or other carrier.

45 To prevent slipping of the hanger the free ends of the hooks 1 are toothed or serrated, as indicated at 4. The plate 2 is formed with a boss 5 which is internally threaded to receive a screw 6 which is pointed at its 50 inner end to make positive engagement with a side of the support 3 and thereby positively hold the device in the required position. A keeper 7 is secured to the plate 2 and is outwardly deflected intermediate of 55 its edge portions to form a socket to receive a standard 8.

A cross piece 9 is provided at the upper end of the standard 8 and its end portions are upwardly bent to provide a frame of substantially U form. A suitable connection 10 secures the cross piece 9 at a middle point to the standard in a manner to admit of the cross piece turning to any angular position. A rod 11 is supported at its ends in the upturned portions of the cross piece 65 9 and receives a roller 12 upon which the lumber is directly supported. The standard 8 is tubular, as indicated most clearly in Fig. 3 and its upper end is constructed to receive the pivot fastening 10. Washers 13 70 are mounted upon the fastening 10 between the upper end of the standard 8 and the cross piece 9 and support the cross piece at such an elevation as to enable it to clear the hanger when turning to adapt itself to the 75 movement of the lumber being loaded or unloaded. The standard 8 is adjustable in the hanger and is secured in the required adjusted position by means of a pin 14 which is adapted to pass through an opening in the socket and through one of the series of openings 15 formed in the standard. A short chain 16 connects the pin 14 with the hanger to prevent loss or misplacement of the pin. 80 85

In practice the device is applied to a side of a coal car or other carrier by passing the hooks 1 over the upper edge of the side after which the screw 6 is turned to cause 90 its inner end to engage or bite into the side 3. The standard is adjusted to the required position and is made secure by the screw 6 in the manner stated. The lumber to be loaded or unloaded is supported upon the roller 12 and is adapted to be tilted and 95 moved thereon, said roller adapting itself so as to enable the lumber to be readily moved and handled.

The foregoing description and the drawing have reference to what may be considered the preferred, or approved form of my invention. It is to be understood that I may make such changes in construction and arrangement and combination of parts, materials, dimensions, et cetera, as may prove 100 expedient and fall within the scope of the appended claim.

Having thus fully described my invention, what I claim as new and desire to 110 secure by Letters Patent is:

A lumber loading and unloading device, comprising a hanger consisting of hooks

and a plate having its opposite ends flanged and secured to the hooks, said plate being provided with an internally threaded boss, a keeper secured at its ends to the plate and having its middle portion deflected to form a vertically disposed socket, a screw mounted in the boss, a standard adjustable in said vertical socket, a cross piece at the upper end of the standard mounted to turn about

a vertical axis, and a horizontal roller carried by the cross piece.

In testimony whereof I affix my signature in presence of two witnesses.

THOMAS E. DUCKWORTH.
